WIRE NEWSPAPER AND BOOKHOLDER

Theodore Russell, Naugatuck, Conn.

Application January 15, 1954, Serial No. 404,170

1 Claim. (Cl. 45—57)

This invention relates to holders, and more particularly to a collapsible device made from wire for holding a newspaper, book or magazine in open inclined position while reading the same.

One object of the present invention is to provide a holder of the above nature comprising a tripod, the rear leg of which is provided with an upturned hook adapted to snap over a forward raised rail connecting the two front legs for detachably maintaining the holder in collapsed position.

A further object is to provide a device of the above nature which will be simple in construction, inexpensive to manufacture, easy to install and manipulate, compact, ornamental in appearance and very efficient and durable in use.

With these and other objects in view, there has been illustrated on the accompanying drawing, one form in which the invention may conveniently be embodied in practice.

In the drawing,

Fig. 1 represents a perspective view of the holder in open position, showing in dotted lines the location of a newspaper when in reading position.

Fig. 2 is a front view of the holder.

Fig. 3 is a side view of the same, showing in dotted lines, the rear supporting leg of the tripod holder located in collapsed position with its lower end hooked over the raised front bottom bar.

Fig. 4 is a side view of the holder with a newspaper resting therein.

Referring now to the drawing in which like reference numerals denote corresponding parts throughout the several views, the numeral 10 indicates generally a newspaper holder, the body of which is formed from wire into a one-piece tripod.

The holder 10 is provided with front legs 14, 15 connected by a pair of forwardly extending horizontal feet 12, 13 which are joined by a forward raised rail 11.

The front legs 14, 15 are connected at their upper ends to a pair of upwardly inclined diverging upper rails 16, 17.

The junctions between the upper rails 16, 17 and the front legs 14, 15 respectively, are joined by a vertical sheet metal clip plate 18 having inwardly-curved ends 19 and 20 embracing said junctions. The clip plate 18 not

2

only serves to reinforce the holder 10, but may have any desired advertising or other indicia placed thereon (not shown).

The upper ends of the diverging upper rails 16 and 17 are joined by curved U-shaped sections 23, 24 to a pair of downwardly converging rear arms 21, 22, the arm 22 extending through a loop 26 on the lower end of said arm 21, and forming a downwardly extending rear supporting leg 25, the bottom end of which has a rearwardly extending upwardly curled hook 27.

One advantage of the present invention is that when the newspaper holder 10 is not being used, the single rear tripod leg 25 may be hooked around the raised front rail 11 of the wire holder for maintaining the same in convenient collapsed condition for shipping or storage (Fig. 3).

While there has been disclosed in this specification one form in which the invention may be embodied, this form is shown for the purpose of illustration only and that the invention is not to be limited to the specific disclosure, but may be modified and embodied in various forms without departing from its spirit. In short the invention includes all the modifications and embodiments coming within the scope of the following claim.

Having thus fully described the invention, what is claimed as new and for which it is desired to secure Letters Patent is:

In a book and newspaper holder, a unitary wire tripod comprising a pair of downwardly extending outwardly divergent front leg portions having forwardly extending feet joined by upwardly extending portions to a horizontally extending straight rail portion spaced forwardly of the plane of said leg portions and above the plane of said feet, a pair of upwardly extending outwardly divergent upper rail portions extending respectively from said leg portions and coplanar therewith, a pair of downwardly convergent rear arm portions joined respectively to said upper rail portions by inverted U-shaped portions, said rear arm portions being disposed in a plane angularly related to the plane of said front leg and upper rail portion, one of said rear arm portions terminating in a loop connected to the other of said rear arm portions, said other arm portion extending downwardly to provide a rear supporting leg and terminating in an upwardly curled hook portion adapted for detachable engagement with said horizontal straight rail portion for collapsing said holder, and a sheet metal clip extending horizontally between the respective junctions of said leg portions and said upper rail portion and having curled end margins embracing said wire tripod at said respective junctions.
